Primary Examiner—Brian N. Vinson*Attorney, Agent, or Firm*—Smith, Hill and Bedell**[57] CLAIM**

The ornamental design for a padlock, as shown and described.

DESCRIPTION

FIG. 1 is a top, front, and left side perspective view of a padlock showing my new design;

FIG. 2 is a front elevational view thereof, the rear elevational view being identical to the front elevational view;

FIG. 3 is a right side elevational view thereof, the left side being a mirror image of that shown;

FIG. 4 is a top plan view thereof; and,

FIG. 5 is a bottom plan view thereof.
